AGITATOR AERATOR FOR LIQUIDS

Filed June 23, 1927

INVENTOR.
Thomas Arthur Rowand
BY Edward A. Lawrence
his ATTORNEY

UNITED STATES PATENT OFFICE.

THOMAS ARTHUR ROWAND, OF PITTSBURGH, PENNSYLVANIA.

AGITATOR AERATOR FOR LIQUIDS.

Application filed June 23, 1927. Serial No. 200,809.

In the preparation of liquids, employed by bread bakeries, it is customary to agitate the same.

In the preparation of the liquid it is placed in a suitable container and is agitated by means of a rotary stirrer which is immersed in the liquid.

It is advantageous also to aerate the liquid for various reasons, and my object is to provide convenient and effective means for simultaneously agitating and aerating the liquid.

I effect this by providing the agitator with air passages leading from the center of the agitator to its perimetral edge or surface, the hollow interior of the agitator being in communication with atmosphere. To increase the effect of the suction which draws the air outwardly through these passages, the same are formed with increasing cross-sectional capacity toward their outer ends, and the passages are so disposed that they trail in reference to the direction of rotation of the agitator.

The air is preferably admitted to the interior of the agitator through an axial bore in the driving shaft, the upper or outer end of said bore being in communication with atmosphere.

Other novel features of construction, and also of arrangement of parts will appear from the following description.

In the accompanying drawings, wherein I have illustrated the best embodiment of the principles of my invention now known to me, Fig. 1 is a vertical section showing the agitator and its driving shaft; Fig. 2 is an elevation of the same; Fig. 3 is a plan view of the agitator base; Fig. 4 is an elevation of the cap of the agitator, and Fig. 5 is an elevation on reduced scale showing the agitator-aerator assembled.

Referring to the drawings, 1 is the container which is provided with a bottom discharge port to which is connected the lead-off pipe 2 having a valve 3. The container is usually of substantially the general contour shown. The agitator, which is immersed in the liquid within a short distance of the bottom of the container is shown comprised of the preferably circular base plate 4 and cap 5, which fits down on the base plate and is detachably secured thereto, as

by the cap screws 5^a whose heads are countersunk in the cap 5. The neck 6 of the cap is cylindrical and internally threaded so that the lower threaded end of the driving shaft 7 may be screwed therein. The upper end of the driving shaft is connected with power means for rotating the shaft and with it the agitator. Thus I have shown the electric motor 8 whose shaft 9 is connected to the shaft 7 by the suitable coupling 10.

The shaft 7 is cylindrical and the central bore 11 is connected to atmosphere at its upper end, as by the radial ports 12.

The lower end of the bore 11 is in communication, by means of the hollow neck 6 of the cap 5, with a central recess or chamber 13 in the base 4 and from said chamber 13 passages 14 lead off to the perimetral surface of the base 4. These passages may conveniently cut or cast in the upper surface of the base, their top walls being formed by the cap 5 when the latter is secured in place.

The passages are of progressively enlarging cross-sectional area toward their outer ends, this increase being preferably provided for by both widening and deepening the passages.

The passages are also arranged to trail relative to the direction of rotation of the agitator which is assumed to be clockwise, as illustrated in Fig. 3.

It is thus seen that the shape and disposal of the passages aids in the application of the centrifugal forces.

It is apparent that while the agitator is stationary the liquid will enter the passages 14 and rise in the bore 11 to the height of the liquid in the container. When the agitator is rotated the centrifugal forces set up in the liquid in the container result in drawing the liquid out of the bore and the passages and also in a reduction of the internal pressure in the liquid in the container. This causes the air to be sucked in from atmosphere through the ports 12, the bore 11 and the passages 14 into the body of liquid where it becomes thoroughly mixed with the latter.

The result is that the proper quantity of air is introduced into and uniformly mixed with the liquid, thus effecting its desired aeration.

No air compressor or other source of supply of air under pressure is thus required.

The introduction of the air also aids in the mixing effect on the liquid by its agitation.

What I desire to claim is:—

1. An aerating agitator having a stem and head, said stem having a bore extending longitudinally therethrough, said head having a central chamber with which said bore communicates and having passages leading from the chamber and opening peripherally of the head, said passages having side walls diverging outwardly from the chamber and having top and bottom walls also diverging outwardly from the chamber, the side walls of each passage forming segmento-cylindrical surfaces curved backwardly from the direction of travel of the head, the side walls of each passage joining the adjacent side walls of the adjacent passages at an acute angle facing the direction of travel of the head.
2. An aerating agitator having a stem and head, said stem having a bore extending longitudinally therethrough, said head having a central chamber with which said bore communicates, said bore having its lower end taperingly enlarged downwardly to the diameter of the chamber, said chamber having passages leading from the chamber and opening peripherally of the head, said passages having side walls diverging outwardly from the chamber and having top and bottom walls also diverging outwardly from the

chamber, the side walls of each passage forming segmento-cylindrical surfaces curved backwardly from the direction of travel of the head, the side walls of each passage joining the adjacent side walls of the adjacent passages at an acute angle facing the direction of travel of the head.

3. An aerating agitator having a stem and head, said stem having a bore extending longitudinally therethrough, said head having a central chamber with which said bore communicates, said bore having its lower end taperingly enlarged downwardly to the diameter of the chamber, said chamber having passages leading from the chamber and opening peripherally of the head, said passages having side walls diverging outwardly from the chamber and having top and bottom walls also diverging outwardly from the chamber, the top walls being horizontal and the bottom walls being inclined downwardly whereby air passing through the passages tends to flow in a slightly downward direction, the side walls of each passage forming segmento-cylindrical surfaces curved backwardly from the direction of travel of the head, the side walls of each passage joining the adjacent side walls of the adjacent passages at an acute angle facing the direction of travel of the head.

Signed at Pittsburgh, Pa., this 21st day of June, 1927.

THOMAS ARTHUR ROWAND.
